UNITED STATES PATENT OFFICE.

MORRIS C. WHITE AND OTHO C. DURYEA, OF CHICAGO, ILLINOIS.

POWER DEVICE.

1,068,195.

Specification of Letters Patent. Patented July 22, 1913.

Application filed December 4, 1911. Serial No. 663,870.

To all whom it may concern:

Be it known that we, MORRIS C. WHITE and OTHO C. DURYEA, citizens of the United States, residing at Chicago, in the county of Cook and State of Illinois, have invented a new and useful Improvement in Power Devices, of which the following is a specification.

Our object is to provide, for attachment to a compressed-air pipe-line, or in connection with a compressed-air supplying system, a cylinder and piston power-translating device adapted to be actuated, more especially, by the force of the compressed air, and provided with means for supplementing and augmenting the driving force of the air in the cylinder against the piston, by introducing into the cylinder, in addition to the compressed-air, a combustible mixture which 20 in burning generates power by its own expansion and by heating the compressed air increases the expansive force of the latter.

The purpose of our invention is, more especially, to economize the use of compressed air in the working of machines or devices which it has been usual to operate by the direct force, or direct and expansive forces, of compressed air, or other incombustible gas, alone.

Our invention is particularly well adapted for certain types of engines, as well as for punching, shearing, forging, riveting, briquetting and pressing machines, generally; but in the present connection it is 35 thought sufficient to illustrate our improvements in the way we prefer to apply them to a riveting machine.

Referring to the drawings Figure 1 is a side elevation of a portable power-riveter with the cylinder, piston and valve-chest in section, the section being taken on line 1 in Fig. 2; Fig. 2, an enlarged section taken on line 2 in Fig. 1, corresponding with line 2 in Fig. 3; Fig. 3, a broken plan-view of the cylinder and attendant parts, showing the cylinder head and certain of its attachments in section, the section being taken on line 3 in Fig. 4; Fig. 4, an elevation of the cylinder-head with certain attachments in section, the section being taken on the line 4 in Fig. 3; Fig. 5, a detached diagrammatic view of an electric igniter; and Figs. 6 and 7, views taken from line 6 in Fig. 3, showing, respectively, a damper in closed and open positions.

The riveting machine is formed with a yoke-frame 10 suspended in the usual way upon a bail 11. On the lower jaw of the yoke is an anvil 12, and slidably mounted in the upper jaw is a bar 13 provided at its lower end with the riveting-tool, or work-performing member, 14. Mounted on the yoke-frame 10 is a stationary cylinder 15 surmounted by a valve-chest 16. The rear end of the cylinder is closed by a cylinder-head 17; and in the forward end of the cylinder is a somewhat contracted opening fitted with a stuffing-box 18 through which works a trunk-piston 19. The stem 20 of the piston is connected through toggle mechanism 21 with the tool-carrying bar 13, in a common manner.

In the cylinder-head 17 is a chamber 22 in open communication with, and forming a contracted continuation of, the interior of the cylinder. The valve-chest 16 covers a seat 23 for a slide-valve 24. In the said seat is a port 25, communicating through a spiral passage 26 with the chamber 22; a port 27, communicating with the annular space 28 in the cylinder about the trunk-portion of the piston; and an intermediate exhaust - port 29. The valve - chest has an inlet-opening 30 which, in practice, is connected with the line - pipe 30^a extending from an air-compressor or compressed air supplier, not shown. Journaled in the valve - chest is a rock - shaft 31 carrying a wing or finger 32, engaging the slide-valve, and provided with an operating-handle 33. When the handle is in an intermediate position the slide-valve closes the three valve-chest ports 25, 27, 29. When moved in one direction it opens the port 25 to the compressed air-supply and exhausts from the port 27 through the outlet 29, and when turned in the opposite direction from the intermediate position it opens the port 27 to the compressed air-supply and opens the port 25 to the exhaust. In the cylinder-head between the chamber 22 and passage 26 is a threaded opening 34 fitted with a bushing 35 forming a tapering passage, or by - passage - port 36. In the wall of the chamber between the bushing 35 and cylinder is a plurality of openings or passages

- 37, forming what may be regarded as the main communication between the passage 26 and chamber 22, and controlled by a damper-ring 38 having perforations 39 and held slidably upon its seat by the bushing 35.
- 5 In the cylinder-head at the passage 26 opposite the bushing 35 is a threaded opening 40 into which is screwed a sleeve-piece 41, surrounded by a nut 42 and having a flange 43 at its outer end.
- 10 The numeral 44 designates a tank for gasoline or other suitable volatile hydrocarbon. On the upper side of the tank is a lug or plate-extension 45 flanged to fit over the flanged end 43 of the sleeve 41 and threaded, as shown, to be engaged by the nut 42 which clamps it in place. In said lug or plate-portion is a passage 46 for air from the passage 26 to the interior of the tank 44.
- 15 Fastened, in the lug or plate 45 is a carbureter-tube 47 having a perforated tapering end extending into the tapering opening, or by-passage-port 36 and fitted with a needle-valve 48 governing its perforation 80 and adjustable from outside the device. Communicating with the interior of the carbureter-tube 47 and extending downward into the tank is a supply-tube 49. The connection of the lug or plate 45 with the sleeve 41, as described, permits the tank 44 to swing 85 and remain horizontal as the riveter-frame is turned to different angles in the vertical plane. In the cylinder-head at the chamber 22 is an opening 50 closed by a cap 51 carrying an electric igniter 52. The igniter consists of a spool of highly refractory heat-conducting material surrounded by an electric resistance wire 53 in circuit with terminals 54 on the cap 51. The igniter 52 at 90 its forward side is in line with the port, or by-passage-port, 36, but back of the main cylinder charging and exhausting ports 37.
- 40 When it is desired to operate the machine, an electric current is turned into the igniter 45 to heat the resistance wire 53 and spool to a red heat. To set a rivet the handle 33 is turned to slide the valve 24 and open the port 25 to the compressed-air supply. As the compressed-air flows from the passage 26 95 through the ports 37 it expands against the piston, and the air passing through the port 36, draws gasoline, or the like, from the spray-opening in the carbureter-tube 47 and the combustible mixture thus produced passes into contact with the igniter 52. The burning and consequent expansion of the mixture causes it to supplement the force which the compressed-air from the main charging and exhausting ports 37 exerts 100 against the piston and by heating said compressed-air it augments the force thereof against the piston which drives the same forward and, through the power-multiplying toggle-mechanism 21, plunges the bar 13 and work-performing member 14 in the direction of the anvil 12. During this movement of the piston air in the annular chamber 28 is exhausted; and to return the piston the handle 33 is shifted to open the port 27 to the air-supply and the port 25 to the exhaust, whereby air enters the chamber 28 and drives the piston backward, and the exhaust in the rear of the piston passes backward through the passage 26 and slide-valve to the outlet 29.
- 15 In the present machine, as we show it, it is not intended to increase the power applied to the piston over that of the compressed air supplied from the pipe-line. In fact, the pressure in the cylinder for driving the piston forward may, in practice, be more or less below that of the pipe-line air. It will be understood that the air from the passage 26 entering through the comparatively small port 36 to the chamber 22 and cylinder would tend initially to become lower in pressure as it expands from the port 36 and the carbureter 47 will only permit sufficient gasoline to be carried inward by the air current to form a combustible mixture, which, in expanding and driving the piston, has a maximum pressure less than would entirely stop the continued inflow of air through the ports 37. This incoming air being out of the path of the incoming mixture does not interfere with the combustion of the latter; but it is heated thereby as stated, and by absorbing heat from the burning mixture it tends to prevent overheating of the cylinder and piston. The relative 100 proportions of the compressed-air and mixture, forced into the cylinder, may be controlled by the damper 38.
- 20 It will be understood that the expansion of fluid in the cylinder retards the inflow from the passage 26, and a great saving in the consumption of compressed air, over what would otherwise be necessary, is effected, and as comparatively little gasoline, or the like, is consumed, there is a great 105 saving over the use of compressed air alone. As the final combustion of the mixture takes place, in or close to the cylinder, heat losses are reduced to a minimum. By locating the ports 37 between the port 36 and the piston, 110 the air entering through the former will have no cooling influence upon the igniter.
- 25 The combustible mixture burns while entering through the cylinder-head, the combustion being continuous during such inflow and not attended with explosions. Any explosions, which would of course momentarily increase the pressure in the cylinder over that of the compressed air-supply, are carefully guarded against in the present 115 construction; but as a precaution to prevent injury in the event that, under any circumstances, an explosion, instead of a comparatively slow burning, of the mixture should occur, we provide in the piston-head a port 120
- 30 35 40 45 50 55 60 65 70 75 80 85 90 95 100 105 110 115 120 125 130

55 closed by a spring-pressed safety-valve
 56. The resistance of the safety-valve
 against opening, in practice, would be more
 or less in excess of the highest working pres-
 5 sure desired in the cylinder, so that in the
 event of an accidental explosion in the cyl-
 inder under any circumstances the safety-
 valve will open and relieve the parts from
 excessive pressure.

10 As the compressed air from the supply
 pipe 30^a is apt to carry moisture which may
 condense in its passage from the valve-chest
 toward the cylinder, and as it is desirable
 15 to prevent water from entering the fuel
 of the tank 44, we provide on the tank an
 outer upright tube 60, closed at the top and
 communicating at its lower end with the
 20 passage 46, and an inner upright tube 61
 communicating at its lower end with the
 tank and at its upper end with the interior
 of the outer tube. Air to maintain gaso-
 25 lene-feeding pressure in the tank must rise
 from the passage 46 in the tube 60 to the
 top of the tube 61, so that any moisture con-
 densed in its passage toward the tank will
 30 be prevented from entering the latter. The
 tube 61 contains a porous plug 62, consist-
 ing of a cylindrical roll of wire-mesh,
 which operates as a screen to prevent any
 hot products of combustion, that may enter
 the passage 46, from exploding the tank
 content.

The foregoing description is intended to
 35 convey a clear understanding of our im-
 provements in what we now believe to be
 the best form of their embodiment, espe-
 cially when applied to a power-riveter, and
 no undue limitation should be understood
 40 therefrom.

40 It is our intention to claim all that is
 novel in our invention and that the claims
 shall be construed as broadly as the prior
 state of the art may warrant.

What we claim as new and desire to se-
 45 cure by Letters Patent is—

1. The combination with a compressed-air
 supplying conduit, of a power-device having
 a cylinder and piston, an air-passage ex-
 50 tendsing from said conduit to the cylinder,
 cylinder feed and exhaust valve-mechanism
 in said passage, and a heater, interposed in
 said passage between said valve-mechanism
 and the cylinder, operating to heat, and
 55 thereby to increase the efficiency of, the pis-
 ton-driving fluid.

2. The combination with a compressed-air
 supplying conduit, of a power-device having
 a cylinder and piston, means for directing
 60 compressed-air from said conduit into
 the cylinder against the piston to drive the
 same, means between the conduit and cyl-
 inder for dividing the compressed-air into
 separate currents, means for mixing fuel
 65 with one of said currents to form a combus-
 tible mixture, and means for igniting said

mixture, the resultant combustion operating
 to heat, and thereby to increase the efficiency
 of, the piston-driving fluid.

3. The combination with a compressed-air
 supplying conduit, of a power-device having
 70 a cylinder and piston, an air-passage extend-
 ing from said conduit to the cylinder, cylin-
 der feed and exhaust valve-mechanism in
 said passage, means, between said valve-
 mechanism and cylinder, for dividing the
 75 compressed-air into separate currents, means
 for mixing fuel with one of said currents to
 form a combustible mixture, and means for
 igniting said mixture, the resultant combus-
 80 tion operating to heat, and thereby to in-
 crease the efficiency of, the piston-driving
 fluid.

4. The combination with a compressed-air
 supplying conduit, of a power-device having
 85 a cylinder and piston, means for directing
 compressed-air from said conduit into the
 cylinder against the piston to drive the same,
 a combustion-chamber between said conduit
 and cylinder, means for dividing the
 90 compressed-air flowing from said conduit to the
 combustion-chamber into separate currents,
 means for mixing fuel with one of said cur-
 rents to form a combustible mixture, and
 means for igniting said mixture as it enters
 95 the combustion-chamber.

5. The combination with a compressed-air
 supplying conduit, of a power device having
 a cylinder and piston, a passage extending
 from said conduit to the cylinder, cylinder
 100 feed and exhaust valve-mechanism in said
 passage, a combustion-chamber interposed
 in said passage between said valve-mech-
 anism and the cylinder, means for dividing
 the compressed-air flowing to the combus-
 105 tion-chamber into separate currents, means
 for mixing fuel with one of said currents
 to form a combustible mixture, and means
 for igniting said mixture as it enters the
 combustion-chamber, the exhaust from the
 110 cylinder passing through said combus-
 tion-chamber and passage.

6. In combination with a power-device
 having a piston and cylinder, a compressed-
 air-supplying conduit, a passage communi-
 cating with said conduit and extending to
 the cylinder behind the piston, cylinder feed
 and exhaust valve-mechanism interposed be-
 115 tween said conduit and said passage, a car-
 bureter interposed in said passage between
 said valve-mechanism and the cylinder, an
 igniter in the path of the fluid flowing to the
 cylinder from the carbureter, and means for
 directing air in addition to that passing
 through the carbureter, and simultaneously
 therewith, to the cylinder, for the purpose
 120 set forth.

7. In combination with a power-device
 having a piston and cylinder, a compressed-
 air-supplying conduit, a main passage com-
 municating with said conduit and extending
 125

to the cylinder behind the piston, hand-operated valve-mechanism, interposed between said conduit and said main passage and movable to supply and exhaust the cylinder,
5 a compressed-air by-passage-port extending from said main passage to the cylinder, a carbureter interposed in said port and an ig-

niter in the path of the fluid flowing to the cylinder from the carbureter.

MORRIS C. WHITE.
OTHO C. DURYEA.
